UNITED STATES PATENT OFFICE.

OTTO KASEL, OF NEW YORK, N. Y.

DIE.

1,308,178.

Specification of Letters Patent. Patented July 1, 1919.

Application filed February 5, 1919. Serial No. 275,234.

To all whom it may concern:

Be it known that I, OTTO KASEL, a citizen of Germany, residing at New York, county of New York, and State of New York, have 5 invented certain new and useful Improvements in Dies, of which the following is a specification.

This invention relates to improvements in punches and dies as used in connection 10 with power presses and particularly to those used for cutting disks containing a central circular opening, commonly known as washers.

The principal object of this invention is 15 to provide a punch and die which will, at one operation form and cut articles requiring piercing and contour shearing of the exterior in a rapid manner.

A further object is to provide means 20 whereby the material is held from buckling or crimping during the cutting operation.

These and other like objects are attained by the novel construction and combination of parts hereinafter described and shown 25 in the accompanying drawings, forming a material part of this disclosure, and in which:—

Figure 1 is a vertical sectional view taken substantially through the center of a punch 30 and die made in accordance with the invention.

Fig. 2 is a plan view of the punch element.

Fig. 3 is a plan and horizontal sectional view of the die element, the section being 35 taken on line 3—3 of Fig. 1, and

Fig. 4 is a vertical transverse sectional view taken substantially through the center of the punch and die, showing a modification thereof.

40 The mechanism comprises a die block 10, substantially rectangular, provided with paired openings 11 near the ends adapted to receive bolts or like fastening devices, whereby the die block may be secured to a bolster or bed of the press as is usual.

A plate 12, formed with the punch holder 18, contains a pair of hardened bushings or sleeves 14, the same slidably encircling guide posts or studs 15 having their lower ends secured in the die block 10, while their upper ends 16 are enlarged and extended toward each other for purposes which will be further on apparent.

Extending above the plate 12, is a punch 55 holder head 18, having a stem 19, containing a small central bore 20, communicating with

an enlarged central annular opening 21, to which is fitted a cylindrical center punch 22, the same being held therein by a taper pin 23, passed through the head 18. The punch 20 extends downward into a further enlarged chamber 24, its walls containing oppositely disposed elongated transverse vertical slots 25, to receive a cross bar 26, having flattened extending outer ends 27 adapted to contact 65 with the lower surface of the heads 16, of the guide posts 15, thereby limiting the upper movement of the bar.

The cross bar 26 passes through a similar slot 28 formed in the punch 22, and also 70 passes through a sleeve or bushing 30, slidably engaged upon the exterior of the punch 22. The lower reduced end 31 of the bushing 30 is slidable within a hardened steel ring or outline punch 33, set in a holder 34, 75 resting against a shoulder therein, the ring 34, in turn resting on a corresponding shoulder formed in the lower surface of the punch head 18.

Thus, as the punch holder is moved up 80 and down, obviously the punch 22 and cutting ring 33 will move with the punch head, but the action of the sleeve element 31 is controlled by the bar 26 operating in the slots 25, the bar being also prevented from 85 rising beyond a definite limit due to the engagement of the overhanging post ends 16.

The plate 12, is connected with the die 90 holder 10, by a pair of guide bolts 36, so as to prevent complete separation of the parts, but permitting the plate 12, together with the punch holder to operate in a normal manner.

Fixed in the die plate 10, is an annular die holder 38, containing a round die 39 the 95 inner diameter 40 of which corresponds with the outer diameter of the punch 22, which forms the central opening through the punching or washer produced, while the outer diameter 41 of the die 39 is adapted 100 to enter within the opening in the punch ring 33, thereby shearing the outline of the washer.

The die 39 is held in intimate relation with the upper surface of the die block by 105 a plate 42 held in position by screws 43 which pass through encircling springs 44, contacting at their upper ends with the bottom of the recesses provided for them, and at their lower ends with the heads of the 110 screws 43, thereby permitting the clamp plate 42 to rise slightly, should the die 39

stick to the punch, while the sleeve 31 is adapted to make contact with the washer material disposed on the upper surface of the die, preventing the thin material from 5 buckling or otherwise becoming distorted.

The material is moved forward when the punch rises in the usual manner, while the punched center part is dropped through the opening 40, and die bed as usual.

10 Having thus described my invention what I claim as new and desire to secure by Letters Patent, is:—

1. In a punch and die for cutting washers, the combination with a die plate, a die 15 movably engaged therein, a pressure plate for holding said die against said die plate, a punch holder, a center punch removably engaged therein, a ring punch secured in said punch holder circumjacent to said center punch, and a pressure sleeve slidably engaged between said center punch and said ring punch.

2. In a punch and die for cutting washers, the combination with a die plate, a circular 25 die block secured therein, a circular die in said die block, a clamp plate spring held to said die block, said clamp plate holding said die in operative position, a punch holder, means for maintaining said punch 30 holder in vertical relation to said die block, means for guiding said punch holder, a cen-

ter punch removably engaged in said punch holder, a ring punch secured in said punch holder circumjacent to said center punch, a clamp sleeve slidably engaged between said center punch and said ring punch, means for limiting the movement of said clamp sleeve, and means for bringing said clamp sleeve downward below the cutting edge in said punch ring prior to the initial movement of 40 the said punch holder.

3. In a punch and die for cutting circular washers having a central aperture, of a die block adapted to be secured to a press, a die plate rigidly engaged therein, a die set in 45 said die plate, means for holding said die resiliently upon said die plate, a pair of vertical guides rigidly fixed in said punch plate, a punch holder having a part slidable on said guides, a pair of bolts for limiting 50 the separation of said punch holder and said die block, a center punch removably engaged in said punch holder, a sliding sleeve on said punch adapted to act as a pressure element on the material to be cut, a ring fixed in 55 said punch holder adapted to cut the exterior of the washer, and means for moving said sleeve downward when said punch is raised to its highest position.

In testimony whereof I have affixed my 60 signature.

OTTO KASEL.
